UNITED STATES PATENT OFFICE.

ALFRED MORGAN POINDEXTER, OF RED BANK, NEW JERSEY, ASSIGNOR OF FORTY-NINE ONE-HUNDREDTHS TO JUSTIN S. GALLAND, OF NEW YORK, N. Y.

SAFETY-RAZOR.

979,559.

Specification of Letters Patent. Patented Dec. 27, 1910.

Application filed September 18, 1909. Serial No. 518,424.

To all whom it may concern:

Be it known that I, ALFRED MORGAN POINDEXTER, a citizen of the United States of America, residing at Red Bank, in the State 5 of New Jersey, have invented a new and useful Improvement in Safety-Razors, of which the following is a specification.

My invention relates to improvements in razors and more particularly to that class of 10 razors known as "safety" razors, and the object of my invention is to provide a razor which, while possessing all the advantages of the "safety" razor, yet overcomes the defects common to this class of razor now in 15 use.

It is obvious that the easiest and most comfortable method of shaving is that in which the least possible resistance is encountered to the cutting of the hair. This, as is well 20 known, can be accomplished only by the proper position of the razor in shaving, in which the lateral surface of the blade is held against the face, and the edge of the blade adjusted diagonally to the line of the stroke; 25 and it is to the ease and facility with which the old style or long blade razor lends itself to this position, that it owes its present 30 superiority over the "safety." Various attempts to adapt this feature to the "safety" 35 razor have heretofore been unsuccessful, for the reason that the present type of construction employed in safety razors renders such a position of the razor in shaving extremely difficult and awkward. The objection was 40 sought to be overcome by surrounding the blade of the old style razor with a frame or guard, but this in practice was found to be not only awkward and unwieldy, but the delicate poise and adjustment of the blade 45 so essential to the successful manipulation of the old style razor, was thereby utterly destroyed.

In my invention hereinafter described, I have succeeded in devising a razor, which, 45 while retaining all the advantages of the "safety" is so constructed, that not only is the proper position of the blade in shaving always assured, but at the same time, the 50 sliding diagonal stroke, conceded to be the correct stroke in shaving, is without any practice or skill on the part of the operator, imparted to the blade. This I accomplish in the manner described and shown in the accompanying drawings, in which—

55 Figure 1 is a top view of my device, Fig. 2

is a side view of the same, Fig. 3 is a view of the cutting member, Fig. 4 is a view of the retaining member, Fig. 5 is a view of the bolt used for securing the parts, Fig. 6 is a perspective view of the guard and handle, Fig. 7 is a view of my preferred form of handle.

Similar characters refer to similar parts throughout the several views.

My device comprises a guard member 1 on the marginal sections or guard sections 65 of which I provide a series of teeth 1' 1'. These teeth are preferably graduated in length. The base 12 of the teeth 1' and the base 12' of the teeth 1' are preferably set 70 in a line obliquely to the longitudinal line of the guard member, and the outer extremities 13 of the teeth 1' and the outer extremities 13' of the teeth 1' are preferably set 75 in a line parallel with the longitudinal line of the guard member. A cutting member or blade 2 is provided to rest upon the guard member 1, and a retaining member 3, narrower than the blade member 2, is placed upon the blade member 2 and 80 held in position by means of studs 4 4' on the retaining member 3, and intended to fit in the apertures 8 8' in the cutting member 2, and in similar apertures 10 10' in the guard member 1. These studs in the 85 apertures in the guard member 1 and cutting member 2 are preferably so placed, as to give the blade member 2 a diagonal position on the guard member 1, so that the cutting edge of the blade member 2 will 90 be nearer the edge of the teeth 1' 1' of the guard member 1 at one end than at the other. I also provide a post 7, upon the guard member 3 to pass through a central aperture 9, in the cutting member 2, and 95 a similar central aperture in the guard member 1, upon which post the hollow handle 5 is placed. In the end of the hollow handle 5, I provide a bolt 6, internally screw threaded at its end section 12 to receive 100 the externally screw threaded section upon the end of the post 7.

I prefer to use the form of handle shown in Fig. 7, substantially square in cross section, as by the use of this form of handle 105 the desired position of the blade in shaving is always maintained; but any handle having two sides thereof parallel may be used to advantage.

In the drawings I have shown my device 110

in the simplest form; but I do not mean to limit myself to the form shown, as my device may be adapted to any form of razor in which guards are used, the essential feature 5 being the blade set diagonally across the same. So too, I do not mean to limit myself to a guard provided with teeth, as the same result may be obtained by the use of any equivalent for teeth.

10 Having thus described my invention, what I claim is:

1. In a device of the character described, a guard member provided with marginal teeth, graduated in length, a cutting member set thereon substantially diagonally to a line drawn through the outer extremities of said teeth, and a retaining member, substantially as shown and described.
2. In a device of the character described, 20 a guard section provided with marginal teeth, a cutting member set thereon substantially diagonally to a line drawn through the outer extremities of said teeth, and a retaining member, substantially as shown and described.
3. In a device of the character described, 25 a guard member, a cutting member set thereon substantially diagonally to a line drawn through the outer extremities of said guard member, and a retaining member, substantially as shown and described.
4. In a device of the character described,

a guard member, having its guard section provided with teeth graduated in length, a cutting member set thereon substantially 35 diagonally to the exterior line of said guard member, substantially as shown and described.

5. In a device of the character described, the combination of a guard member provided with marginal teeth graduated in length, a cutting member set substantially diagonally thereon and parallel to the base of said marginal teeth, a retaining member, and a handle, substantially as shown and 45 described.

6. In a device of the character described, the combination of a cutting member and a guard member provided with marginal teeth graduated in length, whereby in operation the cutting edge is presented obliquely 50 to the line of stroke, substantially as shown and described.

7. In a device of the character described, the combination of a cutting member and 55 a guard member provided with marginal teeth graduated in length, the base line of which teeth is parallel to the edge of the cutting member, substantially as shown and described.

ALFRED MORGAN POINDEXTER.
